Primary Examiner — Prabhakar Deshmukh(74) *Attorney, Agent, or Firm* — Millen, White, Zelano & Branigan, P.C.; William F. Nixon(57) **CLAIM**

The ornamental design for a game apparatus, as shown and described.

DESCRIPTION

FIG. 1 is a right perspective view of a game apparatus showing my new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines shown throughout the views represent the portions of the game apparatus that form no part of the claimed design.
